UNITED STATES PATENT OFFICE.

HARRY MARTIN, OF SALT LAKE CITY, UTAH.

MINER'S KNIFE.

SPECIFICATION forming part of Letters Patent No. 613,698, dated November 8, 1898.

Application filed January 25, 1897. Serial No. 620,656. (No model.)

To all whom it may concern:

Be it known that I, HARRY MARTIN, of Salt Lake City, Utah, have invented an Improvement in Miners' Knives, of which the following is a specification.

My invention relates to a combination tool for the use of miners or others engaged in blasting, and is adapted for splitting, cutting, and reducing the end of the blasting-fuse, for crimping the dynamite-cap onto the fuse, for forming the seat in the cartridge for the reception of the fuse-cap.

The invention consists in the parts, arrangement, and combinations thereof to be hereinafter described, and particularly set forth in the claims.

In order that the invention may be better understood, I have shown in the accompanying drawings a practical embodiment thereof, but desire it to be understood that I do not limit myself to the exact construction which I have therein, for the sake of illustration, delineated.

In the drawings, Figure 1 is a perspective view of my combined tool, showing the fuse cutter and seater open. Fig. 2 is a plan view of the back of the tool, showing the cutter and seater closed. Fig. 3 is a longitudinal section on line 3 3 of Fig. 2. Fig. 4 is a transverse section on line 4 4 of Fig. 3. Fig. 5 is a similar section on line 5 5 of Fig. 3. Fig. 6 is a plan view of the back-springs. Fig. 7 is a sectional view on line 7 7 of Fig. 3.

Referring to the drawings, wherein like reference characters refer to similar parts throughout the several views, 1 represents the sides of a pocket-knife handle, which may be of the usual or any desired material and similar generally to the ordinary pocket-knife handle-pieces. Between these side handle-pieces 1 are hinged blades 2 and 3, as in an ordinary pocket-knife.

4 4 indicate the back-springs for the blades 2 and 3, and 4^a is a division-plate between the blades 2 and 3 at their hinge ends.

The back-springs 4 4, it will be seen from the drawings, are of peculiar shape and are not located, as in the ordinary knife, flush with the back edges of the side handle-pieces, 5 5 but are situated intermediate the edges of the sides, so that the back edges of the latter extend beyond the springs and constitute,

with the back-springs, a sort of trough or box. The springs 4 are concaved or grooved on their back surfaces, as indicated at 4^b, to form 55 a rounded seat or support for the fuse when the latter is being split. The back edges of the side pieces 1 are provided with rounded or substantially semicircular notches 5 and 6, 60 respective notches in the two side pieces being in alinement. Registering with these notches 5 and 6 are similar transverse notches 7 and 8 in the back-springs 4. Pivot on a pin 9, joining the side pieces 1, is a combined tool 10, being provided with a substantially 65 semicircular notch 11, which when the tool is in closed position alines with the notches 5 and 7 in the sides and back-springs. In this notch 11, projecting from the back of the tool, is a crimping-pin 12. Projecting 70 from the tool 10 is a short blade 13, adapted to enter a slot 13^a, formed in or between the back-springs 4 4. This knife-blade is so positioned on the tool 10 that when the latter is being closed it crosses the line of the 75 notches 6 and 8 in the handle and back-springs. A spring 14, secured to the back-spring 4, bears against the under side of the tool 10 and tends to force the latter outward or to its open position. To hold the tool 80 closed within the handle against the tension of this spring 14, I provide a trigger or finger-piece 15, pivoted between the handle sides and provided with a spring 15^a, bearing conveniently against the back-spring 4, and with 85 a projection or lug 15^b, adapted to engage in a notch 15^c in the end of the tool 10.

16 represents the tool used for seating the cap in the cartridge. This tool is pivoted between the handle sides, at the back thereof, preferably on the pivot-pin 9. In order that this may be done, one of the tools 10 or 16 is bifurcated at its hinge end and the other tool is reduced to constitute interlocking hinge-lugs.

17 is a spring also secured to the back-spring 4 and bearing upon the tool 16 in a manner to retain the latter in its closed position. The hinge-lug of the tool 16 is provided with a shoulder 16^a, so arranged that when the tool 16 is opened to a position at right angles to the handle the spring 17 will bear thereon and retain the seating-tool in its open position.

My tool is intended to be used as follows: For cutting the fuse the operator presses on the trigger 15 to release the combination-tool 10, which is forced out or to its open position 5 by the spring 14. The fuse is then laid in the notches 6 and 8 transversely of the knife-handle and pressure applied to the tool 10, which will cause the blade 13 to pass through the fuse and into the slot 13^a in the back-springs, thus making a clean cut without danger of loss of powder from the fuse.

In order to insure the quick ignition of the fuse at the proper time of lighting the same, it is customary, if not necessary, to split the 15 end of the fuse. For this purpose the blade 13 is made use of, the fuse being placed longitudinally in the trough formed by the knife-handle sides 1 and the back-springs 4 after the tool has been released, as before described. 20 It will be seen that pressure on the tool 10 will cause the blade to pass through the end of the fuse, splitting the same longitudinally without loss of powder.

To reduce the end of the fuse, which it is 25 at times necessary to do in order that the same may be inserted into the dynamite-cap, the belled end of the fuse is inserted into one of the notches 5, with its end abutting against the crimping-pin 12. By a gentle 30 pressure upon the tool 10 and turning of the fuse the end of the latter is reduced, so that it can be readily inserted into the cap.

When it is desired to crimp or secure the 35 cap on the fuse, the former, with the cap applied thereto, is placed transversely of the handle in the notches 5 and 7 and the tool 10 forced so that the crimping-pin 12 passes through the cap, driving the metal thereof into the fuse, thus holding the two together.

40 When it is desired to use the tool to make a seat in the cartridge for the cap, the tool 10 is closed and the tool 16 brought to its open

position, when by using the seating-tool as a drill or gimlet a proper seat can be formed in the cartridge.

Having thus described my invention, what I claim, and desire to secure by Letters Patent, is—

1. In a combined pocket-knife and miners' tool, the combination with the knife-handle 50 sides, of a back-spring between the sides intermediate the front and back edges of the sides, a tool 10 pivoted between the handle sides in rear of the back-spring and provided with a longitudinal blade adapted, when 55 closed, to project into a slot formed in the back-spring.

2. In a combined pocket-knife and miners' tool, the combination of separated handle side pieces provided at the back edge thereof 60 with notches 5 and 6, back-springs secured between the handle sides and provided with notches 7 and 8 registering with the notches 5 and 6, a tool 10 pivoted between the handle sides and provided with a longitudinal blade 65 adapted to cross the line of the notches 6, and also provided with a notch 11 adapted to register with the notches 5, and with a crimping-pin 12 in said notch 11.

3. The combination with a pocket-knife 70 handle and blade therein of a back-spring for said blade situated intermediate the edges of the handle, a cutting-tool pivoted between the handle sides in rear of said back-spring, a seating-tool also pivoted between said handle sides in rear of said back-spring, a spring 75 tending to force outward said cutting-tool and a trigger for holding said tool in closed position.

HARRY MARTIN.
